UNITED STATES PATENT OFFICE.

SIDNEY C. RIEKE, OF MINNEAPOLIS, MINNESOTA.

DENTAL CASTING MACHINE.

Application filed August 26, 1925. Serial No. 52,529.

This invention relates to centrifugal casting machines employing a carrier bar, having thereon a molten metal receptacle and a mold carried by said bar on the outer side of said receptacle. Such machines are widely used in the dental profession to cast inlays or bridge-work, and this invention relates especially to a centrifugal dental casting machine.

10 It is the main object of the invention to provide a simple but efficient centrifugal casting machine having means for suddenly and sharply swinging the carrier bar and permitting the same to continue to swing after the momentum has been imparted. In a casting machine of this type, not only must the carrier bar be suddenly swung to pack the gold or other metal in the mold, but the bar must continue to swing for a sufficient 15 length of time to permit the metal packed in the mold to cool and harden. This invention fills both requisites.

15 It is a further object of the invention to provide a casting machine wherein energy, preferably in the form of a compressed gas, may be stored and suddenly released to spin the carrier bar, imparting a sharp initial movement to the same and breaking its driving engagement therewith to permit the 20 spinning of said bar to continue for sufficient time to cool the metal packed by centrifugal force in the mold.

It is a more specific object of the invention to provide in such a device, a piston rod 25 carrying a rack adapted to engage a pinion on the driving shaft, and to suddenly actuate said rod through a short stroke, means being provided for breaking the driving engagement when the rod is moved a predetermined distance.

A still further object of the invention is to provide means for re-setting the device after a casting has been formed for depressing the piston rod whereby a considerable amount 45 of gas will be compressed and stored for future use to actuate said rod and again operate the device.

These and other objects of the invention will be apparent from the following description made in connection with the accompanying drawings, wherein like characters refer to similar parts throughout the several views, and in which:

Fig. 1 is a view partly in side elevation and partly in vertical section of the preferred form of the device; and

Fig. 2 is a fragmentary plan view showing the driving engagement between the piston and the driving shaft.

In the preferred form of the invention illustrated, a square box-like casing or reservoir 3 is provided, having a relatively wide base flange 3^a, adapted to be secured to a supporting surface. A ball valve 4 permits gas or air to be forced in reservoir 3 by means of a pump or other suitable device. The casing 3 carries, at its top portion, the cylinder 5 in communication with one side of the top portion thereof. Port 3^b connects cylinder 5 with reservoir 3. A casing 6 of substantially rectangular shape, having the down-turned flange 6^a and having a relatively small cylindrical portion 6^b adapted to fit over cylinder 5, is secured to the top of reservoir 3 by means of a plurality of bolts 7.

In the flange 6^a of casing 6, opposite the cylinder 5, a plurality of ports 6^c are formed, the purpose of which will later be explained. The top wall of reservoir 3 is recessed somewhat at approximately its center portion to provide a seat for ball bearings 8 and likewise a seat is formed in the boss portion of casing 6 for similar ball bearings 8. The driving shaft 9 is vertically mounted for rotary motion in bearings 8, having its outer end projected somewhat above the boss of casing 6. The carrier bar 10, of standard construction, is rigidly secured to the outer end of shaft 9, carrying at one end the movable crucible or molten metal receptacle 11, on the outer side of which the mold 12 is secured, and, at the other end, the usual counter-weight 13, adapted to be adjusted and rigidly secured to bar 10 by means of the set screw 13^a.

For rotating shaft 9, a piston 14 is provided in cylinder 5, piston rod 15 being preferably of rectangular cross section and carrying a rack 15^a on its side adjacent shaft 9. Rack 15^a is adapted to engage with the pinion 16, rigidly secured to the shaft 9. In the under side of piston rod 15, a pair of notches 17 are provided, one adjacent the outer end thereof which projects slightly beyond casing 6 when the piston is in depressed working position, and the other of which is spaced the distance of

the piston stroke from the outer notch. A spring pressed stud 18 is carried by the casing 6, adapted to engage notches 17, and the operating handle 18^a is secured to the lower 5 end thereof, whereby the stud engagement may be released suddenly when it is desired to operate the machine.

The inner notch 17 is obviously engaged by stud 18 when the rack has been moved 10 through its full stroke, thereby preventing the piston from crashing the pinion 16. The second stop means is provided in the form of a split member 20 rigidly carried by rod 15 adapted to abut the side of casing 6 when the 15 piston has moved through its full stroke. To permit the shaft to continue to rotate and spin arm 10, after the stroke has been given to the rod 15, a cut-out or concave portion 15^b is provided in said rod adjacent the inner 20 end thereof, whereby the engagement between pinion 6 and rack 15^a will be broken when the end of the stroke is reached. A pressure gauge 19 is illustrated on one side of casing 3 conveniently located for observation 25 while the reservoir is being filled with a pump or compressed gas container. In operation, rod 15 is first depressed until the outer notch 17 is engaged by the stud 18, releasably locking the rack 15^a. Air or gas 30 is then pumped into reservoir 3 through the valve 4. An ordinary pump may be used with a connection fitting the entrance to said valve or a compressed gas tube or tank may be connected to said valve by means of a 35 suitable conduit and connection member. The mold 12, of course, is made and molten metal put in the crucible 11. The handle 18^a is then pressed down and promptly released, whereupon the compressed gas will 40 act against piston 14, sharply forcing the same outwardly and imparting a sudden twist or rotation to the shaft 9. Arm 10 will be given a sharp initial impulse and at the end of the stroke of piston 14, will be permitted 45 to continue to rotate. In the type of machine illustrated, using the ball bearings, this rotation will last for a period of about thirty seconds, which will be amply sufficient for the metal forced into the mold 12 to cool. 50 The sharp start given the bar 10 will thoroughly pack the metal into the mold. The ports 6^c at one side of casing 6, of course, permit ready displacement of the air in cylinder 5 and casing 6, so that there will be 55 no considerable amount of back pressure.

When it is desired to again use the device, the piston 14 will be depressed by pressing the end of rod 15 inwardly, thereby compressing a considerable amount of air or gas 60 in the reservoir 3, so that, at most, it will be necessary to only pump a small amount of additional air or gas into the reservoir to obtain the desired pressure for operating the device.

65 From the above description, it will be seen

that applicant has invented a device which will be automatically operative, capable of molding practically perfect castings and fulfilling every need of a centrifugal casting machine. 70

It will be seen that the device comprises few parts and can be manufactured at a reasonable expense.

It will, of course, be understood that various changes may be made in the form, details, proportions and arrangement of parts without departing from the scope of the invention, and that, if desired, other means may be employed to suddenly project the rack 15^a. 75 80

What is claimed is:

1. A centrifugal casting machine having in combination a rotatable carrier, a mold adjacent one end of said carrier, a receptacle for molten metal communicating with said mold and disposed inwardly thereof, means for rotating the said carrier and means for suddenly releasing gaseous pressure against said first mentioned means to suddenly rotate said carrier. 85 90

2. A centrifugal casting machine having in combination a rotatable shaft, a carrier bar rigidly secured transversely of said shaft, a molten metal receptacle adjacent one end of said bar, a mold on the outer side of said receptacle adapted to communicate therewith when said bar is swung, a cylinder adjacent said shaft, a piston working in said cylinder, a piston rod having driving connection with said shaft, and means for suddenly subjecting said piston to a considerable pressure to rotate said shaft and swing said bar. 95 100

3. A centrifugal casting machine having in combination a rotatable shaft, a carrier bar rigidly secured transversely of said shaft, a molten metal receptacle adjacent one end of said bar, a mold on the outer side of said receptacle adapted to communicate therewith when said bar is swung, a reservoir for containing gas under pressure, a cylinder communicating with said reservoir, a piston movable in said cylinder, a piston rod having driving engagement with said shaft, and means for suddenly subjecting said piston to the pressure of the gas within said reservoir to suddenly rotate said arm. 11

4. The structure set forth in claim 3, said shaft having a driving pinion secured thereto, a rack on one side of said piston rod adapted to engage said pinion, and means for breaking the driving engagement between said parts when said piston has moved through a predetermined distance, to permit said shaft to continue to rotate. 12

5. A centrifugal casting machine having in combination a rotatable shaft, a carrier bar rigidly secured thereto, a mold adjacent one end of said carrier bar, a molten metal receptacle disposed inwardly of said mold 13

and communicating at one end therewith, a cylinder adjacent said shaft, a piston working in said cylinder through a predetermined stroke, a piston rod having driving connection with said shaft, means for suddenly moving said piston to rotate said shaft, said piston rod having a recessed portion there-

in to automatically cause disengagement between said driving connection and said shaft when said piston has reached the end of its stroke. ²⁰

In testimony whereof I affix my signature.

SIDNEY C. RIEKE.
